UNITED STATES PATENT OFFICE.

WILLIAM OWEN, OF PETERSHAM, NEW SOUTH WALES.

BOOT OR SHOE.

SPECIFICATION forming part of Letters Patent No. 570,814, dated November 3, 1896.

Application filed March 30, 1896. Serial No. 585,465. (No model.)

To all whom it may concern:

Be it known that I, WILLIAM OWEN, mechanical engineer, a subject of the Queen of Great Britain, residing at Constitution Road, 5 Petersham, in the British Colony of New South Wales, have invented new and useful Improvements in Boots or Shoes for the Purpose of Ventilation, of which the following is a specification.

10 This invention relates to certain improvements in boots and shoes by means of which the connection between the sole of the foot and the outer air is maintained, so that the sole thereof, and consequently the foot therein, will be thoroughly ventilated. Not only will the foot be thoroughly ventilated, but it will be preserved against damp rising through the soles. At the same time this invention 15 prevents squeezing of the foot, and it obviates the use of the intermediate filling of felt or scraps ordinarily used, and it is adapted 20 both for sewed and pegged boots and shoes.

The invention consists in the novel features of construction and in the parts and 25 new combinations of parts hereinafter fully described, and then particularly pointed out and defined in the claims; but in order that this invention may be clearly understood reference will now be made to the drawings here- 30 with, in which—

Figure 1 is a sectional elevation of a boot constructed according to the present improvements. Fig. 2 is a partial sectional plan on line *a a*, Fig. 1. Fig. 3 is a cross-section on line *b b*, Fig. 1. Fig. 4 is a partial back elevation with portion of the upper cut away to show the upright backward extension of the intermediate soles. Fig. 5 is a plan of the top intermediate sole, while Fig. 6 is a similar view of the bottom intermediate sole.

In use I prefer to make my ventilating addition to boots and shoes a merchantable article and prepare it by taking semielastic intermediate soles *C* and *D*, which, for the best 45 class of boots, I prefer to make of aluminium bronze, though such might be made of other semielastic metal or vulcanite or celluloid or some other stiff springy material. These two soles have extension-pieces *C'* and *D'*, which 50 are bent upwardly, and the inner one thereof, *C'*, bent circularly to the shape of the heel of the boot, while the other extension, *D'*, is also

bent circularly, but preferably in two sectors of smaller radius than the radius of the bend of extension *D'*, so that passages or 55 ways are formed by the outside of the extension *D'* on the inside of extension *C'*, the groove *D³*, shown on the outer extension, forming a central recess for the stitching of the galosh or upper of the boot. The extension *C'* of 60 intermediate sole *C* is longer than the extension *D'* of intermediate sole *D*. The top intermediate sole has perforations *C²*, which when said upper intermediate sole is in place correspond to perforations in the insole *B* of 65 the boot, while on the upper face of the bottom intermediate sole *D* are a series of riser-pieces *D²*, which keep said top intermediate sole *C* off the bottom intermediate sole *D*, insuring that a space or series of passages shall 70 be always open between said intermediate soles. These two intermediate soles are riveted or soldered together at the toe and heel, as at *c'* and *d'*, and are then ready for use.

In manufacturing the boot the upper *A* is 75 first secured to the edges of the insole *B* and the welt or strip *B'* sewed or pegged thereto and to the insole, as ordinarily. In the recess or space ordinarily filled with scraps or other filling are placed the intermediate soles *C* and 80 *D*, the extensions *C'* and *D'* thereof taking in the back or heel part *A'* of the upper between the outer material and the lining of said upper, the stiffening material of said heel part being cut away to receive said upper extensions *C'* and *D'*, which thus form part of the 85 stiffening. Through the heel part are perforations *A²*, which are finished off with eyelets and which are placed just above the end of the extension *D'* and before the end of the 90 extension *C'*, so that there is communication from the outer air through the eyelets down the ways or passages *C³*, formed by the bending of the extensions *C'* and *D'* between the two intermediate soles and through the insole 95 to the interior of the boot through the perforations *C²* in the intermediate sole *C* and the perforations *B³* in the insole.

In walking as the sole of the boot is relieved of the weight of the body, as when lifting the 100 foot, the springiness or semielasticity of the upper intermediate sole *C* causes it to buckle or move upwardly, thus sucking the air in through the passages or ways before men-

tioned. When the weight is again placed upon the sole, pressing said intermediate sole onto risers D², such movement causes a flow of the warm air backwardly from between the intermediate soles to the heel-eyelets A². This constant up-and-down movement of the intermediate sole in walking or other movement of the body of the wearer of the boots ventilated by means of my present improvement will insure a thorough ventilation not only of the boot but also of the foot of the wearer.

Having now particularly described and explained the nature of my said invention and in what manner the same is to be performed, I declare that what I claim is—

1. A ventilated boot or shoe having an outer imperforate, and an inner perforated sole, and two ventilating-soles interposed between the same, said ventilating-soles being formed of thin, semielastic material the upper ventilating-sole being provided with openings which communicate with those in the perforated inner sole, and the lower ventilating-sole having risers on its upper surface, the upper ventilating-sole normally lying a little above the ends of said risers and adapted to be depressed by weight and to rise by its elasticity when the

weight is removed, and a passage to the exterior air communicating with the space between said ventilating-soles, substantially as described.

2. A ventilating device for boots and shoes, consisting of an upper and lower sole of semi-elastic material, the upper perforated and the lower sole having risers on its upper surface above the ends of which the perforated upper sole normally lies by its own elasticity and against which it may be depressed by weight, each of said soles having a rearward extension at the heel, that upon the lower sole being the shorter and being provided with a central corrugation forming an air-passage communicating with the space between the two soles which are rigidly united at the toe and at the heel and adapted to lie between the perforated inner sole and imperforate outer sole of a boot, or shoe, the upwardly-bent heel extensions taking the place of and forming part of the heel-stiffening, substantially as described.

Dated this 27th day of February, 1896.
WILLIAM OWEN.
